US0D1062917S

(12) **United States Design Patent** (10) **Patent No.:** **US D1,062,917 S**
(45) **Date of Patent:** **** Feb. 18, 2025**

(54) **EARLY LEARNING TOY**

(71) Applicant: **Shenzhen Liangyuan Technology Co., Ltd.**, Shenzhen (CN)

(72) Inventor: **Sipan Liu**, Shenzhen (CN)

(73) Assignee: **Shenzhen Liangyuan Technology Co., Ltd.**, Shenzhen (CN)

(**) Term: **15 Years**

(21) Appl. No.: **29/853,310**

(22) Filed: **Sep. 14, 2022**

(51) LOC (15) Cl. **21-01**

(52) U.S. Cl.

USPC **D21/615**

(58) **Field of Classification Search**

USPC ..... D21/398, 401, 576, 578, 585, 588, D21/601–605, 615; D11/158–160, 162 CPC A63H 3/003; A63H 3/005; A63H 3/006; A63H 3/50; A63H 3/00; A63H 3/16; A63H 3/12; A63H 3/28; A63H 13/16; A63H 33/00; A63H 33/30; A63H 33/42; A63H 33/003; A63H 11/00; A63H 11/18; A63H 11/20; A63H 9/00; A47G 25/00; A47G 25/005; A47G 25/06; A47G 25/0664; A47G 25/0671; A47G 25/0685; A47G 25/10; A47G 29/00; A47D 13/00; A47K 10/04; G09B 23/36; G09B 19/10
